UNITED STATES PATENT OFFICE.

HEZEKIAH SHANNON, OF CYCLONE, PENNSYLVANIA.

PIPE-DERRICK.

No. 876,243.

Specification of Letters Patent.

Patented Jan. 7, 1908.

Application filed August 22, 1907. Serial No. 389,755.

To all whom it may concern:

Be it known that I, HEZEKIAH SHANNON, citizen of the United States, residing at Cyclone, in the county of McKean and State 5 of Pennsylvania, have invented certain new and useful Improvements in Pipe-Derricks, of which the following is a specification, reference being had therein to the accompanying drawing.

10 My invention relates to improvements in pipe derricks and pertains more particularly to derricks used in drilling oil wells.

The object of my invention is to provide a derrick of this character constructed of pipe 15 sections whereby the same may be more readily set up.

Another object of my invention is to provide a more simple, cheap and effective derrick which can be more readily set up.

20 In the accompanying drawings, Figure 1 is a side elevation of my complete derrick. Fig. 2 is a vertical sectional view showing the means for securing the crown block to the upper end of the derrick. Fig. 3 is a top 25 plan view of the crown block. Fig. 4 is a perspective view of a section of my improved derrick, and Fig. 5 is an enlarged sectional view of one of the standards showing the brace-rods connected thereto.

30 Referring now to the drawings 1 represents the base which is practically made of cement although any other form of base may be used as this forms no part of my invention. Secured to said base by means of bolts

35 2 are the four upwardly extending uprights 3, 4, 5, and 6. These uprights may be of any desired height and are made of sections of pipe. The upper ends of said uprights are screw-threaded at 7 and have a coupling 8

40 screwed thereon, and screwed within the upper end of the coupling 8 are pipe sections 9, 10, 11, and 12, which form a continuation of the pipe sections 3, 4, 5, and 6. The completed derrick is formed of any desired num-

45 ber of sections thus connected together according to the height desired and the length of the section. In order to brace the said sections I provide transverse horizontal brace pipes 13 which have their outer ends

50 flattened at 14 and curved at 15 to correspond with the outer periphery of the coupling 8. It will be seen that two of these braces are thus arranged opposite each coupling, and passing transversely through the

55 curved portions thereof and through the coupling between the pipe sections are bolts

16 by means of which the braces are firmly clamped to the coupling. Riveted or otherwise secured to the flat portion 14 of the brace 13 is the flat portion 17 of the diagonal 60 brace 18 which extends down and is riveted to the brace below opposite the pipe section. The rivet 18' on the opposite side of the brace 13 is secured to the upwardly extending brace 19 which extends upwardly and is 65 secured to the brace above. The braces 18 and 19 are formed of pipe sections similar to the brace 13 only of a less diameter. The bolt 16 passing through the coupling 8 between the upper and lower uprights allows 70 the horizontal braces 13 to be readily removed without disturbing the uprights. This same arrangement allows either the upper or lower uprights to be disconnected from the coupling without disturbing the 75 braces.

In Fig. 1 I have shown the diagonal brace-rods 20 and 21 so arranged that the walking beam may readily operate through the space indicated at 22. The upper ends of the upper section have the crown-block 23 resting thereon. The said crown-block is formed of two I-beams 24 and 25 which are connected together by transverse bolts 26. Surrounding said bolts between the I-beams are pipe 80 sections 27 and 28 whereby the I-beams are held in their spaced position. Passing through the upper ends of the upright are U-bolts 29 having their upper ends passing through flanges 30 of the I-beam, and carried by the upper ends of said bolts above the flanges are nuts 31 by means of which the I-beams are firmly clamped upon the upper ends of the uprights. Carried by the upper 85 face of the I-beams is a transverse lock 32 90 upon which is journaled the shaft 33 carrying a pulley 34 over which the cable 35 passes all of which is well understood by those skilled in the art.

Having thus described my invention what 100 I claim and desire to obtain by Letters Patent, is:

1. A derrick comprising uprights formed of pipes secured together by a screw-threaded coupling, transverse braces formed of 105 pipes and having their ends flattened and curved to conform to the coupling and transverse bolts passing through the curved portion of the braces and through the coupling between the ends of the pipes.

2. A derrick comprising uprights formed of pipes secured together by screw-threaded

couplings, transverse braces formed of pipes and having their ends flattened and curved to conform to the coupling, transverse bolts passing through the curved portion of the 5 braces and through the coupling between the ends of the pipe, obliquely arranged braces formed of pipes and having flattened ends on opposite sides of the flattened portion of the transverse brace, and extending at right angles to each other, and rivets or bolts securing 10 the braces together.

3. A derrick comprising uprights formed of pipes and secured together by screw-threaded couplings, brace-rods secured to 15 said couplings, a crown-block formed of I-beams and resting upon the upper ends of the uprights, and U-shaped bolts passing through the upper ends of the uprights, and through the lower flange of the I-beam, whereby the 20 same is clamped upon the uprights.

4. A derrick comprising uprights formed of pipes and secured together by screw-threaded couplings, brace-rods secured to said couplings, a crown-block formed of two 25 parallel I-beams resting upon the upper ends

of the uprights, U-shaped bolts passing through the upper ends of the uprights and through the flanges of the I-beams, sleeves formed of pipes resting between the two I-beams and transverse bolts passing through 30 the I-beams and the sleeves.

5. A derrick comprising uprights formed of pipes and secured together by screw-threaded couplings, brace rods formed of pipes having flattened ends to correspond 35 with the curvature of the couplings, bolts passing through said flattened ends of the braces and the couplings intermediate the pipes, obliquely-arranged brace rods formed of pipes and having flattened ends resting 40 against the flattened end of the first mentioned braces, and bolts securing the flattened ends of the braces together.

In testimony whereof I affix my signature in presence of two witnesses.

HEZEKIAH SHANNON.
